OVERHUNG TURBO-MACHINE ROTOR ARRANGEMENT

Filed Nov. 27, 1948

UNITED STATES PATENT OFFICE

2,664,268

OVERHUNG TURBO-MACHINE ROTOR
ARRANGEMENTAlan Howard, Schenectady, N. Y., assignor to
General Electric Company, a corporation of
New York

Application November 27, 1948, Serial No. 62,373

2 Claims. (Cl. 253—39)

1

This invention relates to the construction and arrangement of high-speed turbo-machine rotors of the "overhung" type, particularly to such a rotor used as a turbine element in a gas turbine powerplant.

For mechanical simplicity, ease of access to the high temperature rotor, and for other reasons which arise in particular applications, it is often desirable to use in a gas turbine powerplant a turbine rotor having one or perhaps at most two stages supported on a shaft in overhung relation to the shaft bearings. Thus there is no "outboard" bearing to make access to the turbine rotor difficult. Such an arrangement also permits a second low-pressure turbine element to be arranged in other bearings closely adjacent the discharge side of the first rotor. This is particularly advantageous in a compound gas turbine powerplant having a first turbine rotor driving one load device and a second turbine rotor in series flow relation with the first and mechanically independent and driving a separate load device.

Because of the extremely high speeds and high temperature levels at which gas turbine powerplants operate, it is always necessary in the design of such apparatus to consider the possibility that the rotor will experience a minor failure, such as the loss of a small portion of the bucket structure with resulting unbalance of the rotor and increased danger of a major rotor failure. Accordingly, it is an object of the present invention to provide an overhung high temperature rotor arrangement which in the event of the loss of a small portion of the bucket structure will result in the production of a characteristic noise which will notify the operators that a failure has occurred and that the powerplant must be shut down immediately, simultaneously serving to exert a braking effect on the rotor so as to help prevent overspeed, and also acting as an emergency journal bearing to hold the overhung end of the rotor concentric so that any tendency to rotate about an eccentric axis due to the unbalanced dynamic forces resulting from loss of a bucket will be resisted, until the rotor can safely be brought to a stop.

Other objects and advantages will be apparent from the following description taken in connection with the accompanying drawing, in which the single figure represents a sectional view of a high temperature gas turbine rotor having a two-stage bucket wheel arranged in overhung relation to the supporting bearings.

Referring now more particularly to the draw- 55 inner circumferential surfaces 13a, 14a but has

2

ing, the turbine rotor indicated generally at 1 consists of a two-stage welded wheel assembly comprising a first-stage disk 2 having a circumferential row of buckets 3 and secured to, or as shown in the drawing, formed integral with the shaft 4. The disk 2 is actually a built-up welded construction consisting of the central web portion 2a and a rim portion 2b secured together by circumferential welds at 4a. This is the "composite" web construction as shown in my United States Patent No. 2,432,315, issued December 9, 1947, and assigned to the same assignee as the present application. With this construction, the web portion 2a and the shaft 4 may be formed of an inexpensive, easily worked, low-carbon steel, while the rim portion 2b, which is subjected to extremely high temperatures, may be formed of a more expensive, and more difficult to work, austenitic stainless steel. The buckets 3 may, with appropriate design of the bucket wheel, also be welded to the rim portion 2b, or they may be secured by any suitable dovetail arrangement, many of which are known to the art.

The second stage bucket wheel 5 likewise consists of a central web portion 5a, a rim portion 5b, secured by welds 6 and having a circumferential row of buckets 7.

As will be apparent from the drawing, the buckets 3, 7 are provided with axial extensions 3a, 7a which cooperate to form the circumferential inner surface of the fluid flow path between the two bucket wheels. A slight axial clearance is provided between the circumferential edges of these extensions as indicated at 8 so that thermal expansion of these portions of the buckets is permitted without creating any stresses in the buckets or wheels. At the same time, the clearance space 8 is sufficiently small that no substantial amount of hot gas from the motive fluid flow path will circulate into the circumferential space 9 between the two rim portions 2b, 5b.

The adjacent portions of the central wheel webs 2a, 5a are shaped to form an interfitting rabbet having a shrink fit at the circumferential surface 10. It will be seen that the radial surfaces at 11 abut, while a substantial clearance space is provided at 12. The wheel webs are provided with inclined surfaces 13, 14 forming a weld preparation groove in a manner which will be readily apparent from the drawing. At the bottom of the weld preparation groove, the wheel webs are recessed to form a circumferential chamber 15 in which is located a "chill ring" 16. This ring 16 forms a rather snug fit with the

an appreciable clearance space at 17 relative to the second stage wheel web portion 5c. With this arrangement the chill ring serves to "back up" the weld preparation groove and prevents weld metal penetrating into the wheel web portion 5c. It should be particularly noted that the radial separation plane 11 is displaced axially a substantial distance from the plane of the weld so that there is no possibility of weld metal penetrating as far as the surface 11. Thus this design removes the tendency for a crack to progress into a weld from a separation plane between two contiguous surfaces. Furthermore, during the welding and cooling process, the chill ring 16 is free to expand and contract in a radial direction without exerting any stresses on the wheel web portion 5c, the portions of the wheel webs immediately adjacent the surfaces 13, 14 being free to expand and contract somewhat in a radial direction relative to the more massive adjacent portions of the wheel webs.

The shaft 4 is supported in a plurality of main bearings, one of which is shown as a plain bab-bitted journal bearing 18, secured to or formed integral with a support ring 19 which is free to slide axially at the surface 20 in the main frame ring member 21. The frame ring 21 may be considered to be secured by casing structure, not shown, to an outer casing 22, the latter being welded to a continuous main frame ring 23. Supported between the frame ring 23 and the inner frame ring 21 is a turbine nozzle assembly indicated generally in elevation at 24. The details of this nozzle structure are not material to an understanding of the present invention, but are disclosed more fully in the copending application of C. J. Walker and Alan Howard, Serial No. 62,372, filed November 27, 1948, now Patent No. 2,625,013 of January 13, 1953.

The details of the frame ring 23 and related outer casing structure 25 are not necessary to an understanding of the present invention, but it need only be noted that the members 23, 25 form the outer circumferential wall 26 of the motive fluid flow path. It will also be seen that the buckets 3, 7 are of the open-ended or "shroudless" type, defining a close clearance with the circumferential wall 26. The wall 26 carries the stationary interstage blades 27, the tips of the blades 27 defining a close clearance with the axial extensions 3a, 7a of the buckets.

The exhaust passage from the second-stage buckets 7 is defined by inner and outer circumferential walls 28, 29.

In accordance with the present invention, the second-stage bucket wheel is provided with a central axially extending portion forming a narrow smooth annular surface shown at 30, ordinarily defining a comparatively small radial clearance space with an adjacent stationary ring member 31, the latter being welded to the main frame cylinder 32, which is in turn supported from the casing 25 by any suitable means, for instance radial struts shown at 33 extending through streamline shrouds 34 across the hot-gas flow path. The clearance space between the members 30, 31 is sufficiently large that there will be no contact under any normal operating conditions, being for instance of the order of .05 inch at a diameter on the order of 7 inches. It will be seen from the drawing that the bearing surface 30 is roughly the same diameter as the main journal portion of shaft 1.

In order to remove heat from the high temperature wheel rims 2b, 5b, a pair of radiant cool-

ing pads 35, 36 are provided. These may be provided with circumferential ribs or fins presenting an extended radiating surface facing the wheel rims, having interior passages 35a, 36a for the circulation of a suitable coolant such as water. Pad 35 may be conveniently secured by bolts 37 to frame ring 21, while pad 36 may be secured by bolts 38 to a ring 39 which is in turn bolted to the frame ring 31.

Brief reference may also be made to the sealing member 40 which is bolted to the bearing support ring 19, and defines a sealing air chamber 41, to which sealing air at compressor discharge pressure is supplied by suitable conduits, not shown. This high-pressure air flows in the direction indicated by the arrows in the drawing through one or more radial passages as indicated at 42. Part of this air flows to the left through the labyrinth seal 43 to resist the leakage of oil in the opposite direction from the bearing 18, while the other portion of the sealing air flows to the right through the labyrinth seal member 44 to resist the entrance of hot motive fluid into the annular space adjacent the first-stage wheel web. Such leakage of hot gas is also resisted by the circumferential lip formed by an axial extension 3b on the bucket bases, which form a reduced clearance space with the adjacent stationary nozzle ring structure.

The method of operation and utility of the particular parts which constitute the present invention will be seen from the following. It will be readily apparent that the two bucket wheels comprise a considerable overhung mass. During manufacture the bucket wheels and related rotor parts are of course balanced with extreme care. However in spite of careful manufacture and the use of the best available materials, it will sometimes happen that the highly stressed buckets deteriorate in service to the point where part or all of a bucket will fail and leave the bucket wheel. When this happens, even though the mass of the fragment is small, considerable unbalance in the overhung rotor may result due to the extremely high rotational speeds, which may be, for instance, on the order of 10,000 R. P. M. This dynamic unbalance will tend to cause the overhung rotor to vibrate to a degree which makes it imperative that the machine be immediately shut down to avoid serious damage. With the arrangement constituting the present invention, the clearance space between the central bucket wheel portion 30 and the adjacent stationary ring 31 is made sufficiently small that any abnormal unbalance will produce rubbing of the member 30 on the ring 31, with the following results: (1) an ear-splitting "squeal" is produced, which immediately notifies the operator that a failure has occurred and that the machine must be immediately stopped; (2) furthermore, this rubbing action produces a certain braking effect on the rotor tending to prevent overspeeding, or even to reduce the rotor speed; (3) finally, the presence of the rigid stationary ring 31 tends to hold the overhung rotor concentric so that it continues to rotate about its true axis. It will be apparent that if, due to a bearing failure or other serious accident, the rotor should get appreciably off center, the unbalanced forces would become so great as to wreck the entire machine. The strong guard ring 31 acts as an emergency journal bearing and insures that in the event of such a failure the rotor axis cannot move too far from its intended position, so that the unbalanced dynamic forces will be kept

below a value which might result in destruction of the rotor or the entire machine. With the invention, it is entirely possible for the turbine rotor to lose most or all of one bucket without causing substantial damage to the turbine.

In order to perform these functions, it will be obvious that the cooperating cylindrical surfaces on the members 30, 31 must be of appreciable axial length in order to form a bearing surface capable of withstanding the loads imposed when the wheel assumes a sufficiently eccentric position as to produce rubbing.

It is also necessary that the diameter of these emergency journal bearing surfaces be on the order of the diameter of the main journal bearing surfaces of shaft 1, in order that the rubbing velocities will not be so great as to generate friction heat sufficient to cause failure of the parts.

Thus it will be seen that the invention provides an important safety feature in connection with powerplants having massive rotors supported in overhung relation to the shaft bearings.

While only one modification of the invention has been described in detail, it will be apparent to those skilled in the art that many modifications might be made, and it is desired to cover by the appended claims all such changes as fall within the true spirit and scope of the invention.

What I claim as new and desire to secure by Letters Patent of the United States is:

1. In a turbo-machine having a high-speed rotor with a disk portion connected to a shaft supported in main bearing means disposed at only one side of the disk, the combination of a casing supporting the bearing means, an axially extending hub member on the side of the disk remote from the bearing means and defining a smooth circumferential surface concentric with the axis of rotation and of a diameter substantially equal to that of the main bearing means, and a stationary guard ring member supported in the casing and having a circumferential surface forming a small annular clearance space with said hub portion of the disk, said cooperating spaced circumferential surfaces being of appreciable axial length to form a bearing surface whereby any substantial deviation of the disk from its true axis of rotation will result in

rubbing on said bearing surface to produce a characteristic warning sound and a braking effect on the rotor while also acting as an emergency journal bearing to maintain the rotor concentric and thereby reduce the stresses resulting from dynamic unbalance of the rotor.

2. In a turbo-machine having a high-speed rotor with a disk portion connected to a shaft supported in main bearing means disposed at only one side of the disk, the combination of means supporting the bearing, an axially extending hub portion secured to the side of the disk remote from the main bearing and defining a smooth circumferential emergency bearing surface concentric with the normal axis of rotation and of a diameter substantially equal to that of the main bearing means, and a stationary guard ring member rigidly supported in fixed relation to said bearing support means, said guard defining an inner circumferential surface forming a small annular clearance space with said emergency bearing surface, said cooperating spaced circumferential surfaces being of appreciable axial length to form a bearing surface whereby abnormal deviation of the disk from its true axis of rotation produces rubbing on said bearing surface to produce a characteristic warning sound and a braking effect on the rotor while also tending to maintain the rotor concentric and thereby reduce the stresses resulting from dynamic unbalance of the rotor.

ALAN HOWARD.
